UNITED STATES PATENT OFFICE.

JOSEPH W. STORRS, OF NEW LONDON, CONNECTICUT.

RAILROAD-CROSSING.

SPECIFICATION forming part of Letters Patent No. 261,907, dated April 26, 1887.

Application filed January 13, 1887. Serial No. 224,236. (No model.)

To all whom it may concern:

Be it known that I, JOSEPH W. STORRS, a citizen of the United States, residing at New London, in the county of New London and State of Connecticut, have invented new and useful Improvements in Railroad-Crossings, of which the following is a specification.

This invention relates to improvements in railroad-crossings, as set forth in the following specification and claims and illustrated in the accompanying drawings, in which—

Figure 1 is a plan view of a railroad-crossing, parts being removed. Fig. 2 is a section in the plane $\alpha\alpha$; Fig. 1. Fig. 3 is a section in the plane $\gamma\gamma$, Fig. 1.

Similar letters indicate corresponding parts. The letters A B indicate rails of a railway running in one direction, and C D indicate rails of a railway running in another direction. Rail-sections G H are shown as abutting against the rails D, so that the wheels of a car or locomotive can pass uninterruptedly in the direction of arrow 1 along the rails D and rail-sections G H. The rails C are intended to be similarly connected as the rails D; but the rail-sections between the rails C have been removed to expose certain parts to view.

The rail-sections E F, between the rails B in the example shown in the drawings, are at some distance from the rails B, or do not abut against the rails B, and said rail-sections E F in such example shown in the drawings do not obstruct passage along the rails C D. The rail-sections between the rails A have been removed to expose certain parts to view.

The rail-sections G H and E F, with their bases U V and W X, are capable of longitudinal motion on a suitable base or support, J. Guides or ways I, for the bases U V and W X of the rail-sections G H and E F, prevent said rail-sections from becoming displaced, while leaving said rail-sections free to move longitudinally. Bolts or pins Q, passing through suitable slots in the rail-sections, hold said rail-sections together, while leaving said rail-sections free to move longitudinally independently of one another.

When a car or locomotive moves toward the crossing along the tracks A B in the direction of arrow 2, the wheels of said car or locomotive strike against arms or projections K, connected to the rail-sections G H, so

that said rail-sections G H are moved away from the rails D. The motion of the rail-sections G H imparts motion to bell-crank levers 55 L M, connected to said rail-sections. Said bell-crank levers move about suitable pivots or fulcrums, N. When the rail-sections G H are moved away from the rails D, as just stated, one of the bell-crank levers L M imparts motion to the rail-section F, and causes said rail-section F to move toward one of the rails B, while at the same time the other rail-section, E, is moved toward the other rail B, as will be now explained.

The rail-sections E F are connected by suitable devices—such as pivots T—to an arm or plate, S, swinging about a pivot, R. The motion of the rail-section F toward one of the rails B imparts motion to the rail-section E toward 70 the other rail B. Said rail-sections E F can thus be moved to abut against the rails B, so that an unbroken passage will be formed along the rails B and rail-sections E F.

The connection between the rail-sections G 75 H and E F is such that when the rail-sections G H close the passage along the rails D the rail-sections E F rest out of the path of wheels moving along the rails C D, and when the rail-sections E F close the passage along the rails 80 B the rail-sections G H rest out of the path of wheels moving along the rails A B. Suitable bell-crank levers, L M and O P, impart motion to the rail-sections between the rails A 85 and between the rails C. The various rail-sections are so arranged that the rail-sections E F move in common with the rail-sections between the rails C to connect or break the passage along the rails C D, and that the rail-sections G H move in common with the rail-sections between the rails A to break or connect the passage along the rails A B. The bell-crank levers L M and O P swing about suitable fulcrums, N, and said bell-cranks are connected to the rail-sections by suitable means, 90 such as pivots or pins e.

To move the rail-sections G H or E F, I can also employ toes Z, which are adapted to rise above and to move to the level of the rails A B C D. Said toes Z are connected to levers or bell-cranks a b, moving about suitable pivots, c, in suitable arms, d, Figs. 2 and 3. The bell-cranks a b are connected by suitable means—such as pins f—to the rail-sections G

H or E F. As seen in Fig. 2, the motion of the toes Z toward the rails D will move the rail-sections G H, so as to form a continuous passage along the rails D. Similar toes, Z, on the rails B, when pressed toward said rails B, will move the rail-sections E F to form a continuous passage along the rails B.

To prevent snow, dirt, or obstructions from lodging in the paths of movement of the ends 10 of the rail-sections, I use guards Y to cover or shield said paths. Said guards Y, as seen in the drawings, can be formed of two plates or shields of elastic material, such as spring metal. By making the stem of a rail-section 15 (as, for example, the stem F' of the rail-section F, Fig. 3) with a tapering edge, said stem will force said spring-shields of the guard Y apart when said rail-section F moves toward said guard Y. When said rail-section has 20 moved away from said guard Y, the spring-shields of said guard approach closely enough to one another to keep off dirt, snow, and obstructions.

The rail-sections between the main rails A 25 B C D in the example shown in the drawings are adapted to be operated automatically. If desired, a lever, or any suitable device to be operated by hand or by foot, or otherwise, can be applied in any well-known way to operate 30 the rail-sections; but I prefer an automatic operation of said rail-sections.

In the drawings my invention is shown as being applied to railways consisting of lines 35 of rails placed in pairs, such as the rails A B or the rails C D; but said invention can be applied to railways consisting of only one line of rails each, as is the case with some kinds of railways—for example, elevated railways, where the cars are suspended from or run 40 along a single line of rails. When the rail-sections are connected by levers or arms S, as shown in the drawings, it is only necessary to have a tappet or arm, K, on one rail-section, as the movement of one rail-section (as, for 45 example, the rail-section H) will operate the other rail-section; but I prefer to have a tappet or arm, K, applied to each rail-section.

By placing the working parts of the rail-road-crossing on a smooth support—such, for 50 example, as a suitable base-plate, J—said working parts will be enabled to operate easily.

By having the rail-sections automatically operated by a wheel or wheels of a car or locomotive the presence of an attendant to operate the rail-sections is not required.

What I claim as new, and desire to secure by Letters Patent, is—

1. The combination, with the main-line rails, such as D, of two rail-sections, such as G H, ar- 60 ranged against each other in the main-line rails and slidable longitudinally one against the other in opposite directions, so that the end of one section is moved toward one rail of the main rail-line and the opposite end of the 65 other section is simultaneously moved toward the other rail of the main rail-line, substan- tially as described.

2. The combination, with a main rail-line, such as D, of two rail-sections, such as G H, arranged side by side in the main-line rails 70 and slidable longitudinally in opposite directions one against the other, substantially as described.

3. The combination, with the main-line rails, such as B D, running in different directions, 75 of pairs of rail-sections, each pair arranged side by side and inserted in the main lines, and each pair of sections slidable longitudinally in opposite directions one against the other, and connections between the several rail-sections, 80 substantially as described.

4. The combination, with main-line rails, as B D, running in different directions, of pairs 85 of rail-sections inserted in the main lines, and each pair arranged side by side and slidable longitudinally in opposite directions one against the other, and the bell-crank lever L M, having one arm attached to one section of one pair and the other arm attached to one section of another pair, substantially as described. 90

5. The combination, with a main rail-line, such as D, of two rail-sections, such as G H, inserted into said main line, said two rail-sections being movable with respect to one another, and said two rail-sections being connected by a lever or arm, S, substantially as 95 set forth.

6. The combination, with a main rail-line, such as D, of two rail-sections, such as G H, inserted into said main line, said two rail-sections being movable with respect to one another and being connected by a lever or arm, S, and one of said rail-sections being provided with a tappet or arm, K, substantially as set forth. 100

7. The combination, with a main rail-line, such as D, and two rail-sections, such as G H, inserted into said main line, said two rail-sections being movable with respect to one another and being connected by a lever or arm, S, of a toe, Z, and a connection or arm, a b, communicating with one of said rail-sections, substantially as set forth. 105

8. The combination, with a main rail-line, such as D, and two rail-sections, such as G H, inserted into said main rail-line, said two rail-sections being movable with respect to one another, of a tappet or arm, K, applied to each rail-section, substantially as set forth.

9. The combination, with a main rail-line, such as D, and two rail-sections, such as G H, inserted into said main rail-line, said two rail-sections being movable with respect to one another, of shields or guards Y, protecting the paths of said rail-sections, substantially as set forth. 115

10. The combination, with a main rail-line, such as D, and two rail-sections, such as G H, inserted into said main line, said two rail-sections being movable with respect to one another, of a bolt or pin, Q, passing through a slot or slots for connecting said rail-sections, substantially as set forth. 120

11. The combination, with a main rail-line,

such as D, and two rail-sections, such as G H, inserted into said main line, said two rail-sections being movable with respect to one another, of guides or ways I for said rail-sections, substantially as set forth.

5 12. The combination, with the main-line rails, such as D, of two rail-sections, such as G H, arranged side by side in the main-line rails and slideable longitudinally in opposite directions one against the other, and an actuating device to engage a wheel or wheels pass-

ing along said main-line rails and rail-sections for sliding the latter longitudinally one upon the other, as set forth.

In testimony whereof I have hereunto set 15 my hand and seal in the presence of two subscribing witnesses.
